Attorney

UNITED STATES PATENT OFFICE.

FRANK H. GORDON, OF BURNSIDE, ILLINOIS.

SERUM-SYRINGE FILLER.

Application filed June 29, 1922. Serial No. 571,622.

This invention aims to provide a simple means whereby a syringe of the sort used by veterinarians, may be filled with serum or other liquid, this device being facile in operation and being capable of being sterilized readily, the construction being such that no dirt or filth can find its way into the serum, air being prevented from entering the syringe, the device being capable of rapid manipulation, and it being possible to drain the last drop of serum from the receptacle wherefrom the syringe is filled.

It is within the province of the disclosure to improve generally, and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in side elevation, a device constructed in accordance with the invention; Figure 2 is a cross section on the line 2—2 of Figure 1; and Figure 3 is a fragmental longitudinal section, showing the air inlet tube and parts associated therewith.

The numeral 1 marks a receptacle, in the form of a bottle, of the general sort in which serum and the like is supplied to veterinarians, the bottle having a neck 2 provided with a flange 3. A stopper 4, preferably made of rubber, is inserted into the neck 2 and has openings 5. A means is supplied for holding the stopper 4 securely in the neck 2 of the bottle 1, and, with this end in view, recourse is had to a U-shaped yoke 6 provided with inwardly extended fingers 7, adapted to engage the flange 3 of the receptacle 1, as depicted in Figure 1. The yoke 6 carries a clamping device, adapted to engage the stopper 4, the clamping device ordinarily being in the form of a screw 8, threaded into the intermediate portion of the yoke and adapted to bear upon the stopper.

An air inlet tube 9 extends through one of the openings 5 in the stopper 4 and is prolonged to a point closely adjacent to

the bottom of the bottle 1. At its inner end, the air inlet tube 9 is supplied with a seat 10. An operating member 11, ordinarily a rod, is located in the air inlet tube 9 and carries, at its inner end a valve 12, adapted to cooperate with the seat 10 of the air inlet tube. The operating member 11 comprises an enlarged portion 14 which is threaded for adjustment into the outer end of the tube 9, the said portion 14 of the operating member being provided with a turning head 15. The air inlet tube 9 is supplied, adjacent to its outer end, with any desired number of inlet ports 16, about which extends a pocket 17, carried by the inlet tube, the pocket being open at one end. A quantity of filtering material 18 which may be cotton, or the like, is mounted in the pocket 17, and closes the ports 16 against the entrance of foreign material, but not hermetically, it being possible for air to enter the tube 9, through the ports 16 and the filtering material 18. An outlet tube 19, preferably flexible, extends through one of the openings 5 in the stopper 4 and terminates flush with the inner end of the stopper.

The numeral 20 designates a syringe of the kind used by veterinarians for injecting serum, the syringe including a body 21 carrying a nozzle 22 having a lateral inlet 23 wherewith the outlet tube 19 of the receptacle 1 is assembled securely but detachably. A valve 24 is located in the nozzle 22 and is so constructed that the inlet 23 may be closed, the nozzle 22 being opened at the same time, to permit the serum to pass out of the syringe. The construction of the valve is such, further, that the serum may be permitted to enter the syringe through the inlet 23 and through the inner end of the nozzle 22, the outer end of the nozzle being closed. The general operation of such a valve is well known, so that it is not necessary to detail the valve in the drawings. The reciprocating plunger of the syringe 20 is designated by the numeral 25.

In practical operation, the receptacle 1 is inverted, the neck 2 of the receptacle passing through the pocket 27 on the apron 26, or other garment, worn by the operator. The valve 24 may be set so that there is a passage into the body 21 of the syringe by way of the inlet 23 and the inner end of the nozzle 22. The operating member 11 may be rotated, to space the valve 12 from the seat 10

of the tube 9, whereupon air will enter the receptacle 1, through the material 18, through the ports 16 and through the tube 9, the serum being permitted to flow outwardly, through the tube 19, the inlet 23, and the inner end of the nozzle 22 into the body 21 of the syringe 20, when the plunger 25 is retracted. After the syringe has been filled, the valve 24 may be operated to cut off the inlet 23 and to provide an outlet passage through the nozzle 22, whereupon the syringe may be used in the ordinary manner, to inject the serum.

It is to be observed that all parts of the device may be sterilized readily. Air bubbles will not find their way into the syringe, along with the serum. Since the inner end of the outlet tube 19 terminates flush with the inner end of the stopper 4, the bottle 1 may be drained completely. The filtering material indicated at 18 prevents foreign matter from finding its way into the receptacle 1, and the serum therefore, will retain its original purity.

What is claimed is:—

In a device of the class described, a stopper, a receptacle in the bottom of which the stopper is mounted, the stopper having an outlet, an air inlet tube extended through the stopper to a point near to the top of the receptacle, the tube having a lateral pocket which is mounted directly on the tube, the pocket being open at its top, and the stopper being disposed above the pocket, filtering material in the pocket, the tube having a lateral port covered by the filtering material, the port forming a communication between the pocket and the bore of the tube, a stem provided with an enlargement which is threaded into the lower end of the tube, and a valve carried by the stem, the valve cooperating with the upper end of the tube to open and to close the tube.

In testimony that I claim the foregoing as my own, I have hereto affixed my signature.

FRANK H. GORDON.
